UNITED STATES PATENT OFFICE.

GEORGE W. WEISS, OF BROOKLYN, ASSIGNOR TO HIMSELF, AND JOHN STEWART, OF NEW YORK, N. Y.

MACHINE FOR RUFFLING AND GATHERING FABRICS.

SPECIFICATION forming part of Letters Patent No. 417,455, dated December 17, 1889.

Application filed February 28, 1888. Serial No. 265,583. (No model.)

To all whom it may concern:

Be it known that I, GEORGE W. WEISS, of Brooklyn, in the county of Kings and State of New York, have invented a new and useful Improvement in Sewing-Machines for Plaiting and Quilting, of which the following is a specification.

The invention will be hereinafter fully described, and pointed out in the claims.

10 In the accompanying drawings, Figure 1 is a front elevation of a machine embodying my invention. Fig. 2 is a plan thereof, the upper arm of the frame and the needle-operating arm being broken away. Fig. 3 is an 15 elevation of the mechanism whereby the plaits are formed or laid. Fig. 4 represents box-plaiting made by my machine, and Figs. 5 and 6 respectively represent left-hand and right-hand plaiting.

20 Similar letters of reference designate corresponding parts in all the figures.

A designates parts of the main frame of a sewing-machine.

B designates the needle-arm, which is fulcrumed at b.

25 C designates the needle-bar, and C' the cloth-presser or presser-rod, which carries at its lower end the presser-foot C².

D designates the cloth-plate or work-bed 30 of the machine, and E designates the shaft which extends under the cloth-plate and serves to operate the feed-dog e and the looper or rotary hook e', whereby in this example of my invention the thread is looped 35 on the under side of the work in order to form the stitches.

40 Secured to the bed or frame A of the machine is a supplemental frame A', which supports the mechanism that I shall now describe.

Above the cloth-plate D is a carriage F, which comprises a bar F', mounted and adapted to slide in bearings a in the frame A'. In bearings a' in the frame A' is journaled a 45 cam-shaft G, and this cam-shaft receives rotary motion from a pinion g on the shaft E engaging a large wheel g' upon the cam-shaft G. Upon this same shaft G are two cams G' G², which are in this example of the invention 50 secured upon opposite sides of the wheel g'.

The cam G', which is upon the back side of the wheel g', acts upon a truck-roller h on the arm h' of a bell-crank lever which is fulcrumed at h², and the other arm h³ of this bell-crank lever engages by a pin-and-slot 55 connection h⁴ the end of the bar F', which forms a part of the reciprocating carriage. The cam G', acting through the lever h' h³, serves to move the carriage F toward the right hand of the drawings, and upon the bar 60 F' is a tappet h⁵, which is secured in place by a set-screw h⁶, and on which the cam G² acts to move the carriage F toward the left hand of the drawings.

It will be seen in Fig. 1 that each of the 65 canis G' G² has portions of greatest projection at points diametrically opposite each other, and consequently at each complete turn of the wheel g' the carriage F has imparted to it two complete double strokes or two strokes 70 in each direction. As here represented the wheel g' is six times the size of the pinion g, and consequently a double stroke of the carriage F is performed during three revolutions of the shaft E and during three operations of 75 the feed. In the drawings the carriage F is shown at its extreme right-hand position, and an operation of the feed-dog e has just taken place. The next feeding movement takes place when the carriage has nearly reached 80 its extreme left-hand position, and the third feeding movement takes place while the carriage stands still in its left-hand position.

Mounted upon the carriage F are a pair of jaws f f, which come together at their extremities, as shown best in Fig. 3, and which grasp between them the strip of cloth s which is to be plaited, as shown by the black line in Fig. 3. By the reciprocating movement of the carriage F these jaws f, which grasp the 90 fabric between their extremities, carry the fabric forward toward the needle, pressing meanwhile either against the under side of the presser C², which is inclined, as shown in Fig. 3, or against the upper surface of the 95 cloth-plate D. When the jaws f during their inward movement press against the presser-foot C², they form left-hand plaiting, as shown at S in Fig. 5, and when said jaws press against the cloth-plate D they form right-hand plait- 100

ing, as shown at S' in Fig. 6. If the jaws are shifted so as to press during their forward or inward movements alternately against the presser-foot C² and the cloth-plate D, box-
5 plaiting S² will be produced such as is shown in Fig. 4. To provide for thus shifting the jaws f to perform either of the three kinds of plaiting described, I preferably secure them upon a rock-shaft F², which is journaled in
10 the frame F, as best shown in Fig. 2, and which is held against lengthwise movement by collars f' applied to it, also as shown in Fig. 2. The ends of these jaws f may be serrated or formed with fine saw-teeth, as shown
15 at f² in Fig. 2, so as to take a positive hold upon the fabric and to carry it positively forward toward the needle. The rock-shaft F² may be turned in one direction by means of a cam g² upon the shaft G acting upon an
20 arm f³ upon the rock-shaft F², and it may be turned in the other direction by a spring f⁴ applied to the shaft F², as shown in Fig. 2.

The operation of the cam g² upon the arm f³ will be best understood from Fig. 3, the
25 shaft G rotating in the direction indicated by the arrows in Figs. 1 and 3. During such part of the rotation of the shaft G as the cam g² is inactive, as shown in Fig. 3—that is to say, during one operation of the carriage
30 F—the spring f⁴ turns the rock-shaft F² in the direction indicated by the arrow thereon in Fig. 3 and lifts the jaws f into contact with the presser-foot C², so that during their inward movement toward the needle they press
35 against such presser-foot. Before the succeeding inward movement of the carriage F the cam g² comes to bear upon the arm or lever f³ and depresses it, thereby turning the rock-shaft F² in a reverse direction to that
40 indicated by the arrow on it in Fig. 3, and, lowering the jaws f into contact with the cloth-plate D, holds them against the cloth-plate during their inward movement. By this alternate pressing of the jaws f against
45 the cloth-plate and top presser C² is produced box-plaiting like that S² shown in Fig. 4.

If left-hand plaiting is to be produced like that S shown in Fig. 5, the cam g² should be removed entirely from its shaft or slipped out
50 of line with the lever or arm f³, so that the spring f⁴ will hold the jaws f pressed continuously against the presser-foot C².

If right-hand plaiting like that S' shown in Fig. 6 is to be produced, a circular disk having the same radius as the greatest projection of the cam g² should be substituted for such cam, and will then serve to hold the lever or arm f³ down and to maintain the jaws f pressed against the cloth-plate D.

60 Although I have above described the jaws f as being pressed or held against their top presser C² or the cloth-plate D, it will be understood that the material is never held between either of the jaws and the cloth-plate or presser-foot, but is at all times gripped between the two jaws and by them carried in-

ward toward the needle, as distinguished from being pushed in, as is done by a single knife or blade working against the top presser or cloth-plate and grasping the material between it and such presser or cloth-plate. 70

I have represented a gage H as secured to the cloth-plate by a screw i, and against which the edge of the material bears and is guided as it is carried forward by the jaws f. 75

To still further aid in guiding the material in a direct line toward the needle, I have shown upon the carriage F a guide I, which is secured in place by a screw J, passing through a slot j in said guide, and which, 80 therefore, may be shifted so as to cause its guideway to come directly in line with the jaws f. It will be observed that the spring f⁴ causes the rock-shaft F² to hold the jaws f by an elastic pressure against the presser-foot C², and consequently permits the jaws to "give" in passing down the incline of the top presser C². The size of the plait may be varied by changing the position of the forward tappet h⁵ upon the bar F' of the carriage, and provision is afforded for such adjustment by the set-screw h⁶, which secures said tappet on said bar. 85

I do not desire to limit my invention to the guide I, fixed upon the carriage F, as it 90 may be, with nearly equal advantage, secured in stationary position to the fixed frame of the machine.

What I claim as my invention, and desire to secure by Letters Patent, is— 100

1. In a sewing-machine, the combination, with stitch-forming mechanism, of a feeder, a work-plate, a presser-foot, a carriage, two cams for imparting longitudinal movement to said carriage, a shaft upon which said cams are arranged so as to extend in opposite directions from said shaft, a rock-shaft on said carriage, a cam for rocking said shaft in one direction, a spring for rocking it in the other direction, and a pair of jaws both mounted upon said rock-shaft and adapted to press against either the presser-foot or the work-plate, substantially as specified. 105

2. In a sewing-machine, the combination, with stitch-forming mechanism, of a feeder, a work-plate, a presser-foot, a carriage having a reciprocating motion in the line of feed, a pair of jaws on said carriage between which material to be plaited passes and is moved along, a single rock-shaft on the carriage upon which both said jaws are directly supported and by turning which said jaws are caused to press upon the work-plate or presser-foot, as desired, and an adjustable guide mounted on said carriage and through which the material to be plaited passes, substantially as specified. 110

GEORGE W. WEISS.
